CLAIM

The ornamental design for video game accessory, as shown and described.

DESCRIPTION

FIG. 1 is a rear perspective view of a first embodiment thereof, showing, for reference, another video game accessory coupled thereto;

FIG. 2 is a rear view thereof;

FIG. 3 is a front view thereof;

FIG. 4 is a top view thereof;

FIG. 5 is a bottom view thereof; and,

FIG. 6 is a left side view thereof.

The broken lines shown are included for the purpose of illustration and form no part of the claimed design.
